Primary Examiner — Selina Sikder(74) *Attorney, Agent, or Firm* — Manabu Kanesaka(57) **CLAIM**

The ornamental design for controller for cooling apparatus, as shown and described.

DESCRIPTION

FIG. 1 is a front view of a controller for cooling apparatus showing our new design;

FIG. 2 is a rear view thereof;

FIG. 3 is a right side view thereof;

FIG. 4 is a left side view thereof;

FIG. 5 is a top plan view thereof; and,

FIG. 6 is a bottom view thereof.

The broken lines are shown for environmental purposes only and depict portions of the controller for cooling apparatus that form no part of claimed design.
